UNITED STATES PATENT OFFICE

2,426,972

LINER FOR GUN BARRELS

John P. Magos, Wilmette, Ill., assignor to Crane
Co., Chicago, Ill., a corporation of Illinois

Application November 27, 1944, Serial No. 565,255

1 Claim. (Cl. 89—14)

1

This invention relates to liners for gun barrels or the like. More particularly, it relates to a novel type of liner in which the relative ease of renewability and economy of construction are significant features. In order to acquire a better understanding of the background concerning my invention, it should be understood that the bores of guns made of the usual materials when fired for an extended period become severely eroded in a region extending from the commencement of the rifling to about four calibers beyond. The erosion of the bore results in subsequent decreased velocity, accuracy and range and, after a time, the barrel must be discarded. There have been numerous methods suggested for remediying this situation such as the insertion of short replaceable liners positioned in that portion of the gun where the erosion is most severe, but, to my knowledge, most of these constructions have been more expensive, less easy to accomplish the replacement and considerably more difficult to remove when replacement has become necessary. The latter difficulty is especially significant when it is realized that repairs and replacements are frequently made in the field under emergency conditions and where suitable tools and equipment may be lacking.

Difficulties encountered with the designs previously referred to have led to the development of a design which it is believed overcomes all previous difficulties and in addition possesses many advantages over those previously tried. A further important object is to provide a liner having a substantially circular taper over its entire length and which preferably employs a flange at its breech end, the latter being held securely to the gun barrel by means of suitable holding means, the latter serving not only to hold the liner within the barrel, but also aiding in the removal of the liner for repairs and inspection.

A further important object is to provide a holding means in which the latter serves also as an index and guide in assuring proper and accurate alignment of the liner and its rifling with the rifling of the barrel and which is preferably so designed that such positioning of the liner cannot be incorrectly inserted.

Another important object is to provide for a flanged renewable liner in which the end limits are adequately protected against injury in the course of handling the barrel and liner assembly.

A still further important object is to provide a flanged type of liner which may either be of the same material as the barrel, or which may be lined with a metal having desirable wear char-

2

acteristics such as a metal alloy or composition consisting of cobalt and at least two of the metals of the chromium group. Or the liner itself may be completely constructed of such desirable metal or composition.

Other objects and advantages of the design of the instant invention lie in the relative ease of manufacture, greater accuracy in machining, elimination of substantial clearances between the liner and barrel and the relative ease in which the latter members may be assembled and disassembled. These and other advantages will be more clearly brought out in proceeding with the specification read in light of the accompanying drawings, in which:

Fig. 1 is a sectional assembly view of a gun barrel and liner embodying my invention.

Fig. 2 is an enlarged fragmentary sectional view of the end portion of the assembly described in connection with Fig. 1.

Fig. 3 is an end view showing the flanged portion and bolting arrangement of the liner in its assembly with the barrel shown in Figs. 1 and 2.

Fig. 4 is a sectional view of a modified form of liner.

Fig. 5 is a sectional view of the modified form of Fig. 4 taken on the line 5—5 of Fig. 4.

Fig. 6 is a further modified form of the invention, in which the liner end portion is enclosed.

Referring now to Fig. 1, the gun barrel 1 is provided with a suitably tapered bore 2 within which the similarly tapered liner 3 is fitted, forming with the barrel 1 a gas sealed joint, as indicated by the tongue and groove joint as at 4, to accommodate the annular beaded end 5 of the liner 3. The end portion 5 may be rounded as shown to fit snugly within the receiving groove but the form described is not absolutely essential.

Directing attention now to the breech end of the gun barrel, the liner 3 is provided with a flange 6, the latter member being held to the gun barrel by means of the bolts 7. The latter members are positioned so as to extend through the counterbored holes 8 in the flange and to engage the threads of the tapped holes 9 in the end of the gun barrel 1. The bolts as shown in Fig. 2 are preferably distributed uniformly around the flange so that the tightening of the liner within the barrel may be done gradually and uniformly around the bolt circle. In lining up the rifling 11 of the liner accurately with the rifling 12 of the barrel, one bolt or, if desired, two of the bolts preferably diametrically opposite one or several tapped holes 9 may be of an odd size and form

so as to assure the correct positioning of the liner within the barrel, considering especially the location of the rifling. A longer tapped hole 13 is illustrated in Fig. 1 as an example of one way in which a pilot or dowel bolt (not shown) may serve the function of guiding the liner in its course of assembly with the barrel 1.

In connection with allowing for the convenient removal of the liner 3, it should be noted, as shown more clearly in Fig. 3, that a number of tapped holes 10 are preferably spaced alternately between the holes 8 which are preferably counterbored as indicated. The tapped holes 10 have for their purpose the provision of means for allowing the bolts 7 to be removed from the barrel engaging position shown in Fig. 1 to threadedly engage the tapped holes 10 of the liner 6. The bolts 7 then bear against the end of the barrel 1 as shown in Fig. 2 upon suitable rotation. Thus the easy removal of the liner 3 is accomplished. It will be apparent now that the liner may be extracted from the barrel 1 by simply transferring the bolts 7 from the holes 8 and the respective tapped holes 9 to the tapped holes 10 in the flange. Each bolt is successively tightened evenly against the end 20 of the barrel, thereby forcing the flange 6 away from the barrel to extract the liner. It will be apparent that the complete assembly provides for a substantial frictional surface contact along the taper of the liner for virtually the entire length of the latter member. This is desirable not only in preventing any tendency to turn during the action of the projectile leaving the barrel but it also supports the liner adequately against any outward distortion because of the complete surface support provided by the inner portion of the gun barrel itself.

While the foregoing description has concerned itself with a construction using a substantially unbroken taper in the liner it may be desirable to prevent undue torque otherwise tending to cause the rotation of the liner within the barrel by other means. A modified form of construction may be employed in which the liner 3a shown in Fig. 4 may be tapered for a relatively short portion of its length, as indicated at 14. As shown more clearly in the sectional view of Fig. 5, the end portion of the liner adjacent its flange 6 may be of oval cross-section. Otherwise the construction including the taper is similar to that employed in Figs. 1 and 2, but the liner may be oval in form to further act as a safeguard against rotation. The tapped holes 21 for removal of the liner may be used, with the counterbored holes

22 employed for the purpose of securing the liner within the barrel, the latter member being tapped as at 23. For suitable assembly with a carriage (not shown) the gun barrel 1 may be threaded as indicated at 15.

In order that the flange 6 may be protected, it may be desirable as shown in Fig. 6 to counterbore the barrel 1 as at 18, with the flange shouldering as at 19. The bolts 17 are used to draw the flange and liner 3b inwardly toward the barrel to make the desired seat.

It should be apparent that numerous modifications may be made without departing from the spirit of the invention as expressed in the claim 15 appended hereto.

I claim:

20 A gun barrel construction, the combination including a barrel, a tapered liner therefor, means for retaining the said liner in substantially immovable position relative to the said barrel, the said retaining means including a flanged retaining member constituting an integral end portion of the said liner, the said retaining member having annularly spaced apart threaded and unthreaded apertures, and having annularly positioned bolt means for engagement with the unthreaded apertures and with the end of the said barrel to hold the said liner in substantially axially immovable position relative to the barrel, 25 the said bolt means being removable to cooperate with the threaded apertures of the said flanged retaining member whereby upon annular repositioning of the said bolt means in the threaded aperture to bear against a transverse end surface 30 of the said barrel the said liner is axially movable relative to the barrel for replacement or repair.

JOHN P. MAGOS.
